(57) CLAIM

I claim the ornamental design for a men's undergarment, as shown and described.

DESCRIPTION
